SWINGING PANEL DISPLAY

Jerome Folkart, New York, N.Y.
(116-16 Queens Blvd., Forest Hills, N.Y. 11375)

Filed Jan. 2, 1974, Ser. No. 429,835

Term of patent 14 years

Int. Cl. D20—02

U.S. Cl. D6—139

FIG. 1

FIG. 3

FIG. 2

FIG. 5

FIG. 4

FIG. 1 is a front elevational view of a swinging panel display showing my new design.

FIG. 2 is a rear elevational view, slightly reduced in scale, of FIG. 1.

FIG. 3 is a top plan view of FIG. 2.

FIG. 4 is a bottom plan view of FIG. 2.

FIG. 5 is a side elevational view of FIG. 2 as seen from the right thereof, the view from the left thereof being substantially identical.

I claim:

The ornamental design for a swinging panel display, substantially as shown and described.
